(57) CLAIM

The ornamental design for a combined belt buckle and money clip attachment, as shown and described.

DESCRIPTION

FIG. 1 is a front elevation view of a combined belt buckle and money clip attachment showing my new design.

FIG. 2 is a back elevation view thereof.

FIG. 3 is a left side elevation view thereof.

FIG. 4 is an end elevation view thereof.

FIG. 5 is a top plan view thereof.

FIG. 6 is a bottom plan view thereof.

FIG. 7 is a top, rear perspective view thereof; and,

FIG. 8 is another perspective thereof.

The broken lines in FIGS. 5-8 represent portions of the combined belt buckle and money clip attachment and form no part of the claimed design.

1 Claim, 3 Drawing Sheets
